UNITED STATES PATENT OFFICE.

GEORGE E. DOW, OF DENVER, COLORADO, ASSIGNOR OF ONE-HALF TO
CHARLES M. McCABE, OF SAME PLACE.

SAFETY DEVICE FOR ELEVATORS.

SPECIFICATION forming part of Letters Patent No. 520,844, dated June 5, 1894.

Application filed February 24, 1894. Serial No. 501,387. (No model.)

To all whom it may concern:

Be it known that I, GEORGE E. DOW, a citizen of the United States, residing at Denver, in the county of Arapahoe and State of Colorado, have invented certain new and useful Improvements in Safety Devices for Elevators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention is a safety device for elevators whereby the starting of the elevator while the door is open is prevented.

The invention consists in certain novel features hereinafter described and claimed.

20 In the annexed drawings, Figure 1 is a plan view of my improved device showing it arranged to permit the passage of the elevator and Fig. 2 is a similar view showing the device arranged to prevent the passage 25 of the elevator.

In carrying out my invention, I secure to the side or bottom of the elevator car or cage the fixed jaw A and the guides B which may be formed integral or separate from each 30 other, as preferred, and consist of flat metallic plates having longitudinal grooves in their inner edges as shown. The sliding jaw C is mounted in the guides and slides along the same to and away from the fixed jaw so 35 as to release the operating lever or cable or clamp the same against the fixed jaw. The outer end of the sliding jaw is engaged and operated by a pinion D which is preferably constructed in the form of a segmental gear 40 meshing with a rack bar E on the side of the sliding jaw, the pinion being mounted on one of the guides which is partly cut away to accommodate the same. The pinion is provided with a lever arm F which projects be- 45 yond the elevator car into the path of the door which leads into the elevator well. The outer end of this lever arm is adapted to be struck and operated by the door, G, and is provided with a small roller H to reduce the 50 friction and wear on the door. The lever arm is held normally outward by a spring I, as shown, and a stop J is arranged in the

path of the lever arm to limit the movement of the same and prevent it from being drawn too far backward by the spring.

55

The operation of the device will be readily understood. When the landing is reached, the door is opened and is thus brought against the end of the lever arm so as to swing the same around and impart motion therethrough 60 to the sliding jaw, forcing said jaw inward and clamping the operating cable or lever against the fixed jaw. The cable will thus be securely held against movement and consequently the elevator cannot be started while the door is 65 opened. As soon as the door is closed, the spring returns the lever arm and sliding jaw to their initial positions and the elevator can then be started.

My device is entirely automatic in its operation and is obviously simple and efficient.

Having thus described my invention, what I claim, and desire to secure by Letters Patent, is—

1. A safety device for elevators consisting 75 of a clamp adapted to grasp the operating cable or lever and comprising a fixed jaw, guideways extending from said fixed jaw, a sliding jaw mounted in the guideways, a pinion engaging the sliding jaw to force the same 80 against the operating cable or lever, and means for rotating said pinion.

2. The combination of the elevator well door, the fixed jaw, the sliding jaw, a pinion 85 engaging the same and having a lever arm projecting into the path of the said elevator well door, and a spring acting on said lever arm in opposition to the said door.

3. The combination of the elevator well door, the fixed jaw, guide-ways extending 90 from said jaw, a sliding jaw mounted in said guideways and having a rack bar formed on one side, a pinion engaging said rack bar and having a lever arm projecting into the path of the elevator well door, a spring acting on 95 said lever arm in opposition to the said door, and a stop arranged in rear of the lever arm to limit its movement.

In testimony whereof I affix my signature in presence of two witnesses.

GEORGE E. DOW.
